UNITED STATES PATENT OFFICE.

EDWARD CONWAY WREN, OF COUNTY OF DEVON, ENGLAND.

COMBINED CAMP-BED AND VALISE.

1,079,971.

Specification of Letters Patent.

Patented Dec. 2, 1913.

Application filed November 17, 1911. Serial No. 660,762.

To all whom it may concern:

Be it known that I, EDWARD CONWAY WREN, a subject of the King of Great Britain, residing in Devonshire, England, 5 have invented certain new and useful Improvements in and Relating to Combined Camp-Beds and Valises, of which the following is a specification.

This invention relates to beds of the combined camp bed and valise class.

The present invention has for its object to provide an improved construction of beds of this kind, and to this end provides an improved construction and arrangement of 15 the end bags, an improved arrangement of the strips of webbing upon the canvas whereby not only is the tendency of the said canvas to sag greatly reduced, but the spring or elasticity of the canvas is increased and 20 the comfort of the sleeper is enhanced.

The invention further provides the various other improvements in details of the bed which are hereinafter more fully described and pointed out in the claim.

25 In order that the invention may be the better understood, drawings are appended in which:—

Figure 1 is a plan of the underside of a bed constructed in accordance with the present invention. Fig. 2 and Fig. 3 are plans to an enlarged scale of a detail of construction. Fig. 4 is a perspective view of a leather socket for the cross stays or stretchers. Fig. 5 is a side view of one end of the 35 bed in use. Fig. 6 is an end view showing the arrangement of the cross stays or stretchers, the bed being omitted. Fig. 7 is an end view showing an alternative arrangement of the cross stays. Fig. 8 is a side view showing a preferred form of attachment for the ends of the flexible stays. Fig. 40 9 is a perspective view showing an alternative form of bag for the ends of the canvas. Fig. 10 shows the method of attachment of the bag to the canvas. Fig. 11 shows a further modification of a bed constructed in accordance with the present invention. Fig. 12 shows the bed illustrated in Figs. 1 to 5 in the packed or folded condition. Fig. 13 shows the bed illustrated in Fig. 11 in the packed or folded condition. Fig. 14 shows an alternative form of cover.

Referring to the accompanying drawings, 50 *a* indicates a sheet of canvas which at each end is provided upon each side with narrow extensions *a'*, perforated as shown, and to

which are secured bags *a*², the sides of which comprise triangular shaped pieces *a*³, the whole forming an oblong bag having triangular shaped sides, one of which is provided at each end of the canvas *a*, and which bags are designed to receive the kit. Secured upon the underside, and at each end of the canvas *a* are strips of webbing *b* which at one end extend beyond the limits of the canvas *a* and form axial loops *b''* which when the bed is pitched are hooked over pegs whereby the longitudinal stability of the bed is secured. The strips of webbing *b* curve outwardly to reach the side of the 60 canvas where they are turned back or folded to form opposite pairs of loops *b*² similar to that shown at *c'* in Fig. 2. While the body of the webbing is secured by sewing upon each side to the canvas, the line of said sewing is stopped at a point upon the outer edge 65 clear of the end of the loop so that the said loop is quite free of the canvas.

c indicate short lengths of webbing which are disposed diagonally of the canvas and are provided at their outer ends with loops *c'* such as the loops *b*² and like them not secured to the canvas. The loops of the respective strips are engaged one with another as shown in Fig. 3, and within the engaged 70 loops is placed a conical socket of leather or other durable material *d*, Fig. 4, which may be secured in position by means of a few stitches as indicated at *d'* Fig. 3. The leather or the like projects somewhat beyond 75 the loops thereby facilitating the engagement of the stretchers. By this means there is provided on each side of the canvas a pocket or receptacle into which the ends of transverse stays or stretchers supporting the 80 said bed may be readily inserted. By arranging the webbing in the manner just above described, the formation of a transverse ridge in the canvas at the points where the legs or stretchers are inserted in the canvas, is 85 avoided as also the sudden fall of the said canvas. The curving of the webbing moreover provides a side and cross strain whereby the sagging of the canvas is reduced. The bed is supported as in the former instance by means of pegs or supports indicated by *e*, and of which two are provided at each end of the bed as shown. The aforesaid supports while not being connected to 90 the canvas have secured to them by means of eyes or the like, indicated generally by *f*, the ends of the diagonally disposed struts or 95 100 105 110

stretchers g the upper ends of which engage the aforesaid pocket formed at each side of the bed. The diagonal struts g at their lower ends engage metal or other sockets h^1 formed at each end of a strap h resting upon the ground and having attached to it at each end a cord, wire or other flexible body h^2 , the upper end of which is attached to the eye f secured to the struts g as shown in Fig. 6.

i indicates cords or the like attached at one end to the sides of the canvas and disposed upon each side thereof at or about the center of its length. The said cords are provided for the purpose of closing the mouths of the bags and lacing up the sides of the bed when packed, using the gromets provided for that purpose. These cords are also useful, when the bed is prepared to keep the blankets from touching the ground by being loosely tied across the center of the bed outside and on the top of the blankets. The bed when packed presents an appearance substantially as shown in Fig. 12.

25 Where the flexible body h^2 is formed of wire, I prefer to provide a known means of attachment for the ends as shown in Fig. 8, in which case a ferrule or sleeve h^5 is employed through which the end of the wire is passed, and which wire is then formed into a loop, the free end of the wire being formed into a loop disposed outside the sleeve with the end inside. By this means any tearing or damage to the canvas or 35 the kit from the end of the wire is effectively prevented.

Instead of arranging the bags at each end of the canvas, a single bag may be provided at one end only. I may also in some cases 40 arrange the bags as shown in Figs. 9 and 10. In this case the bag comprises a rectangular bag j open at one end, said open end being provided with flaps j^1 , j^2 , j^3 one or more of which may have a suitable fastening device 45 thereon, as indicated generally on flap j^3 , Fig. 9. The bag is secured to the end of the canvas by inserting the end inside the mouth of the bag and sewing it thereto, the flap j^3 being disposed as shown in Figs. 50 9 and 10, and the flap is suitably incised for the passage of the curved pieces of webbing b . The bag j serves to contain the kit and when required for transport it may be rolled up very compactly, and as shown in 55 Fig. 13, the flap j^3 is then secured by a suitable fastening upon one of the end loops of the web b .

The bed may in some instances be provided with a waterproof cover k which when desired may be elevated at one end by means 60 of a stick or other means, a sword may be used, for this purpose, the said stick, sword, or other means resting on the ground, the top of the stick or button on the hilt of a sword being passed through a button-hole 65 provided at the center of the head end of the cover. One end of a string or the like is attached to the button-hole, and the other end to the outer peg, thus staying the support. The general appearance of the arrangement when in use is illustrated in Fig. 11.

I may in some instances provide a cover such as shown in Fig. 14, in which case an opening is formed in the cover k as indicated by the dotted lines k^1 in Fig. 14. Placed above the opening is a piece of material which is secured to the cover on three sides as shown in the aforesaid Fig. 14. By this means when the cover is in position 80 the head may be passed through the opening k^1 and the cover then forms a sort of hood. When the head is withdrawn the cover prevents the entry of wet. This arrangement however is known and forms no part of my 85 invention.

Claim:

A camp bed consisting of a main member of flexible canvas adapted to extend under the body of the user, strips of webbing secured to the underside of the main member and extending diagonally from the side portions of the main member at points spaced inwardly from the opposite ends of said member and toward the center thereof, the 90 outer ends of said strips having free loops located near the side portions of said main member, and a strip of webbing secured to the underside of each end portion of the main member and extending from points adjacent the outer ends of said first strips and in concave curves toward and beyond the ends of said main member to provide supporting loops, the inner ends of said second strips having free loops, said loops being mountable on vertical supports and distributing the strain on said main member to maintain an equal tension thereon.

Signed in the presence of the two undermentioned witnesses.

EDWARD CONWAY WREN.
